BY

Tom Wright,

ATTORNEY.

UNITED STATES PATENT OFFICE.

ELIGHA BRUDEN, OF SAN FRANCISCO, CALIFORNIA.

SPARK-PLUG.

No. 888,782.

Specification of Letters Patent.

Patented May 26, 1908.

Application filed February 10, 1908. Serial No. 415,018.

To all whom it may concern:

Be it known that I, ELIGHA BRUDEN, a citizen of the United States, residing at San Francisco, in the county of San Francisco and State of California, have invented new and useful Improvements in Spark-Plugs, of which the following is a specification.

This invention relates to spark plugs for explosive engines, the object of the invention being to provide an improved form of a spark plug, the use of which will not be accompanied by the deposition of carbon upon the plug, and which will therefore remain clean for an indefinite period.

15 In the accompanying drawing, Figure 1 is a side view of my improved spark plug; Fig. 2 is a longitudinal sectional view of the same, the holder being shown in side elevation; Fig. 3 is a side view of the porcelain wire holder; 20 Fig. 4 is a sectional view thereof.

Referring to the drawing, 1 indicates a porcelain holder, through which pass wires 2 and 3 connected with platinum terminals 4, 5. The long wire 2 extends through the whole 25 length of the plug, and is provided with the usual binding screw 6, but the short wire 3 passes through only the thick inner portion of the holder, and its end 7, terminates in the sloping rear surface or shoulder 8 of said 30 thick portion. Upon the outer end of said holder is placed the inner sleeve 9, which has a conical inner surface adapted to contact with the end 7 of the short wire 3, its outer surface being threaded and screwed into the internally threaded sleeve 10, which is 35 formed tapering or conical on the inside to conform to the inner sloping surface of the holder, a sheet 11 of asbestos being interposed between said sloping surfaces. By 40 screwing said sleeve 10 upon the sleeve 9 the latter is drawn tightly against the exposed end of the wire 3. The sleeve 10 is externally threaded, in the usual manner, as shown at 45 12, for the purpose of screwing it into the wall of the explosion chamber. The advantage 50 of this construction is that both of the platinum points are separated from metallic parts by a sufficient body of porcelain to prevent any deposition of carbon on either of 55 said points. When one of said terminal points is connected with metal close to said point, as has been the custom, there is a tendency for carbon to deposit on said material,

so that, in time, due to this coating the spark plug becomes very inefficient. With my improved spark plug, this objection is avoided.

I claim:

1. A spark plug having a wire holder of non-conducting material and having a rear shoulder, two wires therethrough, having exposed points adjacent to each other, between which the spark can pass, one of said wires extending to the outer end of the holder, and the other wire extending to said shoulder and being there exposed, and a metallic sleeve for the holder in contact with said exposed end and provided with means for securing it in the wall of an explosion chamber.

2. A spark plug comprising a wire holder of non-conducting material, two wires extending therethrough, and terminating in adjacent points, one of said wires extending substantially the full length of said holder, means for connecting said wire with an electric circuit, the other wire extending only to an intermediate portion of said holder, a metallic sleeve around said holder arranged in contact with the end of said latter wire, and a sleeve screwed to the first sleeve, and provided with means for securing it in the wall of an explosion chamber, substantially as described.

3. A spark plug comprising a wire holder of non-conducting material, two wires extending therethrough, and terminating in adjacent points, one of said wires extending substantially the full length of said holder, means for connecting said wire with an electric circuit, the other wire extending only to an intermediate portion of said holder, a metallic sleeve around said holder arranged in contact with the end of said latter wire, a sleeve screwed to the first sleeve, and provided with means for securing it in the wall of an explosion chamber, and a sheet of asbestos interposed between the second sleeve and the holder, substantially as described.

In testimony whereof I have hereunto set my hand in the presence of two subscribing witnesses.

ELIGHA BRUDEN.
